UNITED STATES PATENT OFFICE.

PETER AITCHISON, OF NEW ROCHELLE, NEW YORK, ASSIGNEE TO AMERICAN BANK
NOTE COMPANY, OF NEW YORK, N. Y., A CORPORATION OF NEW YORK.

ART OF CONDITIONING PRINTED PAPER.

1,115,150.

Specification of Letters Patent.

Patented Oct. 27, 1914.

No Drawing.

Application filed February 7, 1913. Serial No. 746,844.

To all whom it may concern:

Be it known that I, PETER AITCHISON, a subject of the King of the United Kingdom of Great Britain and Ireland, residing at New Rochelle, in the county of Westchester and State of New York, have invented certain new and useful Improvements in the Art of Conditioning Printed Paper, of which the following is a specification.

My invention relates to the art of conditioning printed paper, and more particularly to paper which has been dampened previous to receiving the impression thereon.

In printing upon paper by the planographic or undersurface printing methods, it is usually necessary to dampen the paper before running it through the press. When prints are made in two or more colors, or each sheet is printed upon both sides, it is the general custom to dampen the paper prior to the taking of each impression, which is made necessary by the drying of the paper, or its partial drying, between runs, and the resultant shrinkage which would result in a loss of register. In addition to the repeated dampening of the paper, it is necessary after each sheet is completely printed, to refinish the paper in a manner to obliterate those inequalities due to its shrinkage after being so dampened. The usual treatment of the paper during printing also includes the insertion of sheets of ordinary dry tissue paper between each sheet as it leaves the press, and the succeeding printed sheet, to avoid offsetting from one to the other. In actual practice the tissue sheets receive any offset which occurs and in addition to the liability of slightly defacing an imprint, this paper tends to absorb moisture from the printed sheet and thus aggravate those other conditions eliminating moisture which necessitate redamping.

With these conditions in mind, the main object of my invention is to provide an art of conditioning paper after it has been printed, by which offsetting of any description will be minimized and the moisture in the paper will be retained in sufficient volume to admit of a plurality of impressions being made without necessitating the redamping of the paper during the completion of the printing thereon.

A further object is to so treat the paper

as to permit the addition of moisture thereto, or its diffusion therethrough, if desired, between runs.

A still further object is to provide an art of conditioning paper whereby after an impression has been made therefrom, each sheet of paper will have the atmospheric air excluded therefrom in large measure to prevent evaporation of the damping fluid, and avoid the necessity for redamping. And a still further object is to provide an art whereby after the final run of each sheet, the sheets may be accumulated and a large number thereof refinished without likelihood of offsetting and by the mere application of sufficient pressure to insure a perfect flattening of each sheet.

The invention consists primarily in an art of conditioning printed paper, including therein the bringing of an insert sheet of material coated with a substance having no affinity for the oily or greasy vehicle of the ink and rendering said material impenetrable to atmosphere and substantially non-absorbent, in contact with the printed surface of sheets of dampened paper; and in such other novel methods as are hereinafter set forth and described and more particularly pointed out in the claims hereto appended.

In the practice of my invention, sheets of previously dampened paper are run through a planographic or engraving printing press in the usual manner, receiving an imprint with ink having a greasy or an oily vehicle. As each sheet of printed paper is delivered from the press, the surface of the paper having the imprint of fresh ink thereon is covered with a sheet of paper or other flexible material coated with a non fluid substance, insoluble by the damping fluid or the vehicle of the ink, such as Ceresine wax, Japan wax, paraffin wax, or other analogous material having no affinity for the greasy or oily vehicle of the ink with which the sheet contacts. Hence there is no tendency of the impression to offset upon this insert sheet, and the likelihood of the smutting or blurring of the imprint in spots is avoided. Furthermore, the coating upon this insert sheet will close the pores thereof in a manner to make it impenetrable to atmosphere and thus prevent evaporation of the damping fluid with which the sheet of paper is impregnated. Successive sheets are brought

into a pile including an insert sheet for each printed sheet. This pile of sheets by reason of the exclusion of the air from the greater portion thereof, may be held for several days without becoming sufficiently dry to prevent the making of a perfect imprint thereon without redamping, and as the surfacing of the insert sheets is insoluble by the damping fluid or the vehicle of the ink, and substantially non-absorbent, the printed sheets in each pile will be rendered more mellow by this treatment. Not only does an anti-offset sheet of this character prevent the evaporation of the damping fluid in the printed sheet, but the slight absorptive properties of a thin coating of wax will tend to diffuse such fluid in a manner to insure uniformity in the condition of each sheet. Furthermore, all sheets in a pile will be similarly conditioned as the effect of each insert sheet is limited to the surface of the sheets contacting therewith. After being piled in the manner described, the sheets must be maintained at a temperature below the melting point of the coating material.

I have discovered by the actual practice of the invention, that when sheets are not sufficiently damp after any run, the use of insert sheets of the character above referred to, which have themselves been slightly moistened, will restore the desired mellow condition to the printed sheets, and distribute the added moisture uniformly throughout the printed sheets. After the final run of each sheet, a pile of such sheets are accumulated, a sheet of presser board coated with the same material as the sheets used after each preceding run being inserted between the printed sheets. The pile is then subjected to heavy pressure for a sufficient period to insure the elimination of all irregularities in the surface of the printed sheets.

By using coated presser board, a smooth surface is secured, the moisture from the printed sheets not entering these boards and the pores thereof being so closed by the wax coating as to present a smooth surface and thus prevent the transfer of the design of the texture of the presser board to the finished sheet of paper. Furthermore, off-setting upon the presser boards is prevented.

In actual practice, I prefer to use insert sheets of dimensions greater than those of the printed sheets, so as to permit the former to overlap the latter and thus protect the edges thereof from atmosphere.

By the practice of my improved art, I not only am enabled to make several runs on a sheet of dampened paper, without redamping it, but I am enabled to make successive runs without those delays incidental to such drying of the ink as is necessary preparatory to the redamping process. With hand dampened paper, forty-eight hours are fre-

quently required to properly condition or mellow the paper, and as cloths are used which are capable of absorbing the ink, great care must be exercised and further delays frequently result. Hence I am not only enabled to avoid the expense and other undesirable incidents resulting from the redamping of the paper, but am enabled to make another run as soon as the ink of the preceding impression is sufficiently dry not to smut in handling in the press.

The insolubility of the coating of the insert sheets by the damping fluid or the vehicle of the ink, prevents any of the coating material entering the fiber of the paper, or combining with the ink of the impression, in a manner to interfere with the taking of an imprint, or the offsetting of an impression already made.

Having described the invention, what I claim as new and desire to have protected by Letters Patent, is:—

1. An art of conditioning printed paper including therein the bringing of an insert sheet of material coated with a substance having no affinity for the oily or greasy vehicle of the ink, and rendering said material impenetrable to atmosphere and substantially non-absorbent, in contact with the printed surface of a sheet of dampened paper upon delivery from the press and allowing said sheet and said insert to stand until required for another run of the press whereby the ink on said paper is prevented from off-setting upon said insert sheets and the moisture is retained in said paper and is diffused throughout same.

2. An art of conditioning printed paper including therein the piling of freshly printed, dampened sheets of paper with insert sheets contacting with the printed surface of each sheet, said insert sheets being coated with a substance having no affinity for the oily or greasy vehicle of the ink and rendering them impenetrable to atmosphere and substantially non-absorbent and allowing said sheet and said insert to stand until required for another run of the press whereby the ink on said paper is prevented from off-setting upon said insert sheets and the moisture is retained in said paper and is diffused throughout same.

3. An art of conditioning printed paper including therein the piling of freshly printed, dampened sheets of paper alternated with insert sheets coated with a substance having no affinity for the oily or greasy vehicle of the ink and rendering them impenetrable to atmosphere and substantially non-absorbent and allowing said sheet and said insert to stand until required for another run of the press whereby the ink on said paper is prevented from off-setting upon said insert sheets and the moisture is retained in said paper and is diffused throughout same.

4. An art of conditioning printed paper including therein the piling of freshly printed, dampened sheets of paper with insert sheets contacting with the printed surface 5 of each sheet, said insert sheets being coated with a substance having no affinity for the oily or greasy vehicle of the ink and rendering them impenetrable to atmosphere and substantially non-absorbent, each said insert 10 sheet being dampened before being used and allowing said sheet and said insert to stand until required for another run of the press whereby the ink on said paper is prevented from off-setting upon said insert sheets and 15 the moisture is retained in said paper and is diffused throughout same.

5. An art of conditioning printed paper including therein the bringing of an insert sheet of material coated with a substance 20 having no affinity for the oily or greasy vehicle of the ink, and rendering said material impenetrable to atmosphere and substantially non-absorbent, in contact with the printed surface of a sheet of dampened paper upon delivery from the press after all 25 runs excepting the last, piling such printed sheets after the final run with alternate sheets of presser board coated with a substance having no affinity for the oily or

greasy vehicle of the ink, and rendering them impenetrable to atmosphere and substantially non-absorbent, and subjecting the pile to continued pressure, whereby the surface of all printed sheets therein is finished.

6. An art of conditioning printed paper including therein the bringing of an insert sheet of material having a coating of a wax having no affinity for the oily or greasy vehicle of the ink, and rendering said material impenetrable to atmosphere and substantially non-absorbent, into contact with the freshly printed surface of a sheet of dampened paper, and allowing said sheet and said insert to stand at a temperature below the melting point of the wax until required for another run of the press whereby the ink on said paper is prevented from off-setting upon said insert sheets and the moisture is retained in said paper and is diffused throughout same.

In witness whereof, I have hereunto affixed my signature in the presence of two subscribing witnesses, this 31 day of January, 1913.

PETER AITCHISON.
